US00D640191S

(12) **United States Design Patent**
Like et al.

(10) **Patent No.:** US D640,191 S
(45) **Date of Patent:** ** Jun. 21, 2011

(54) **ENERGY STORAGE DEVICE**

(75) Inventors: **Nathan Like**, Westland, MI (US);
Robert F. Gutman, Fraser, MI (US)

(73) Assignee: **Flextronics International Kft.**, Tab
(HU)

(**) Term: **14 Years**

(21) Appl. No.: **29/305,028**

(22) Filed: **Mar. 12, 2008**

(51) **LOC (9) Cl.** 13-02

(52) **U.S. Cl.** D13/104

(58) **Field of Classification Search** D13/102-106,

(57) **CLAIM**

The ornamental design for an energy storage device, as shown and described.

DESCRIPTION

FIG. 1 is a front perspective view of an energy storage device showing our new design;

FIG. 2 is a front elevational view of the energy storage device shown in FIG. 1;

FIG. 3 is a rear elevational view of the energy storage device shown in FIG. 1;

FIG. 4 is a left side elevational view of the energy storage device shown in FIG. 1;

FIG. 5 is a right side elevational view of the energy storage device shown in FIG. 1;

FIG. 6 is a top plan view of the energy storage device shown in FIG. 1; and,

FIG. 7 is a bottom plan view of the energy storage device shown in FIG. 1.
